Attorney

UNITED STATES PATENT OFFICE

151,944

DESIGN FOR A KITE

George E. Shackelford, West Columbia, Tex.

Application December 6, 1946, Serial No. 135,312

Term of patent 3½ years

(Cl. D34—15)

To all whom it may concern:

Be it known that I, George E. Shackelford, a citizen of the United States, residing at West Columbia, in the county of Brazoria, in the State of Texas, have invented a new, original, and ornamental Design for Kite, of which the following is a specification, reference being had to the accompanying drawings, forming a part thereof.

Figure 1 is a plan view of a kite, showing my new design.

Figure 2 is a side view thereof and;

Figure 3 is a front edge view thereof.

I claim:

The ornamental design for a kite, as shown.

GEORGE E. SHACKELFORD.
